UNITED STATES PATENT OFFICE

ALBERT H. MARTY, OF CLEVELAND, OHIO

MOUNTING FOR PLATE GLASS WINDOWS

Application filed November 3, 1928. Serial No. 316,999.

This invention relates to mountings for windows such as are used in store front or display window construction, show case construction, door construction, transom construction, sash construction, and the like.

More specifically, in the embodiment illustrated this invention discloses an improved mounting of this type in which the constituent elements are relatively heavy sections. These sections are preferably formed by extrusion and composed of non-corrosive metals such as bronze, brass, or other suitable alloys. It is to be understood, however, that this invention is not limited to the use of metal as other materials may be used without departing from the spirit of my invention.

One object of this invention is to produce an improved mounting for windows which is strong, substantial and durable in construction and handsome and artistic in appearance and composed of sections not likely to be injured or distorted in normal handling or in the usual manufacturing hazards and which are not easily disfigured or sprung in use.

Another object of this invention is to produce an improved mounting for windows in which the elements are simple in form and easy to produce and which are economical to fabricate and erect and which are easy to dismantle for removing or renewing the glass when replacements become necessary.

A further object of this invention is to produce an improved mounting for windows in which the outer clamping member is uniform in appearance throughout its length and free from any openings, projections or recesses required for adjustments, so as to facilitate cleaning or polishing and to eliminate the accumulations of polishing material at or adjacent to the irregularities.

A further object of this invention is to produce an improved mounting for windows in which there are no tightening means on the exterior, in which the tightening means are invisible from the exterior of the glass and, in fact, a mounting in which the tightening means are completely concealed either from an exterior or interior observer.

A further object of this invention is to pro-

duce an improved mounting for windows in which the outer clamping member is of uniform section throughout its length and in which any portion will co-operate with the devices for drawing this clamping member toward the glass, that is an outer clamping member in which there are no regularly spaced holes, projections or attachments which must register with correspondingly spaced adjusting devices on the stationary member.

A further object of this invention is to produce an improved mounting for windows which utilizes an improved form of tightening device purposed to hold the glass accurately and firmly in position and yet in a yielding or resilient manner so that the glass will not be subject to danger of fracture.

A further object of this invention is to produce an improved mounting for windows specially adapted for that type of display window having an inclined display board approximately adjacent to the inner edge of the mounting.

A further object of this invention is to produce an improved mounting for windows provided with a novel type of moisture collecting trough.

Further objects and advantages of this invention will appear from the following description and upon reference to the accompanying drawings.

The annexed drawings and the following description set forth in detail certain means embodying this invention, such disclosed means constituting however, but a few of the forms in which the principle of my invention may be applied.

In said annexed drawings:

Figure 1 is a vertical cross-section through my improved mounting, this cross-section being taken through one of the tightening devices, this section being taken from the plane indicated by line 1—1 of Figs. 9 and 10 and showing the several elements of this invention in their assembled position and supporting the glass.

Fig. 2 is a view similar to Fig. 1 but is taken in a different plane showing one of my improved tightening brackets in elevation,

this section being taken from the plane indicated by line 2—2 of Figs. 9 and 10.

Fig. 3 is a detached fragmentary perspective view of the stationary member or inner 5 clamping member of my improved window mounting.

Fig. 4 is a detached fragmentary perspective view of the movable member or outer clamping member used with my improved 10 mounting.

Fig. 5 is a detached perspective view of one of the slideable tightening brackets used with my improved mounting.

Fig. 6 is a detached fragmentary perspective view of an extension trough member preferably used with this improved mounting.

Fig. 7 is a view similar to Fig. 1 but showing the slideable bracket in its released position and showing the movable clamping member and the extension trough member in broken lines to indicate the facility with which these members may be put in place or removed.

Fig. 8 is a modified application of this improved mounting in which the extension trough mounting is not utilized.

Fig. 9 is a broken plant view of my improved mounting partly in section taken from the plane indicated by line 9—9 of Fig. 1.

Fig. 10 is an outside elevation of my improved mounting partly in section taken from the plane indicated by line 10—10 of Fig. 1.

Fig. 11 is a view similar to Fig. 1 illustrating, however, a slightly different form of movable clamping member and slideable bracket.

Fig. 12 is a detached perspective view of the slideable bracket used in the construction illustrated in Fig. 11.

Fig. 13 is a view similar to Fig. 11 but showing the slideable bracket in its released position and showing the movable clamping member in broken lines to illustrate the facility with which this member may be put in place or removed.

Fig. 14 illustrates an application of my improved mounting to a door frame or the like.

Fig. 15 is a view similar to Fig. 8 showing another slightly modified form of this invention.

I shall first describe the form of the invention illustrated in Figures 1 to 10 inclusive, wherein my invention is shown applied to store front construction. While, as illustrated, this mounting is shown supporting the lower edge of a window, it will be understood that the same or similar construction may be used for the side or top of the window.

In these figures, 1 indicates the glass to be mounted and 2 represents the frame or sill of the building upon which this improved window mounting is placed. This sill may 65 be constructed of any suitable material, wood

being shown in the illustrations. The outer face 3 of this sill may be finished with wood, cement, granite, marble, or other durable and artistic facing material. The display space interiorly of the glass 1 may be flat 70 somewhat as shown in Figure 8, or may be occupied by a display board 4 placed in position close to the window as is shown in Figure 1. An open space 5 is left between the display board 4 and the window mounting for a purpose to be hereinafter pointed out.

The main or base member of my improved mounting is a stationary or inner clamping member 6 which is secured to the building 80 sill by means of screws, expansion bolts, or in any other manner desired. The type of connection selected will depend to a large extent upon the material of which the building frame is made, wood screws 7 being suggested as the connection, in the drawings. 85

The stationary member 6 is formed with a contacting lip 8 at its upper end adapted to engage the inner face of the glass 1, which is to be supported. Adjacent to the contacting lip 8, the stationary member is 90

preferably formed with an arcuate trough 9 intended for the collection of moisture or condensation which forms on the window. For the purpose of draining the moisture from this trough, weep holes 10 are provided. The 95 inner or lower edge of this trough is bounded by a flange 11 which projects vertically from the lowermost point of the arcuate curve as shown. The stationary member 6 is further formed with a vertical wall 12 which is 100 substantially in vertical alignment with the flange 11 and which forms the extreme rear or inner portion of the member 6. The stationary member 6 is further provided with a horizontal flange 13 which extends 105 outwardly from the base of the vertical flange 12 to a point considerably beyond the plane of the window as clearly shown in Figure 1. This flange 13 terminates with a down-turned edge 14, which, however, forms 110 no part of my invention. This stationary member 6 is illustrated in the detached fragmentary perspective view, Fig. 3.

The outer or movable clamping member 15 is formed at its upper end with a contacting lip 16 which is adapted to contact the glass 1. The lower edge 17 of this outer clamping member 15 tightly contacts the flange 13 of the stationary member 6. The intermediate portion 18 of this outer clamping member may have any contour which is desired to satisfy the artistic appearance required. Attached to this intermediate portion 18 of the clamping member is a reversed or re-entrant lip 19, this lip being reversed or re-entrant in the sense that it points in a direction opposed to its clamping movement. This lip 19, in the form of the invention shown in Figures 1 to 10 inclusive, is connected to the intermediate portion 18 of the outer 125

clamping member 15 by means of a relatively thin web 20. Drain openings or recesses 21 are provided in the lower edge of this outer clamping member 15 to permit the escape of any moisture which may have drained in through the holes 10 or from any other source. This outer clamping member 15 is clearly shown in the detached fragmentary perspective view, Figure 4.

10 Mounted for sliding movement on the horizontal flange 13 of the stationary member 6 is a bracket 22. This bracket is formed at the left or outer end with a reversed lip or hook member 23 adapted to interlock with the reverse lip 19 on the member 15, this lip 23 being connected to the base portion 24 by a vertical section 25. The inner or rear end of this sliding bracket 22 is formed with a substantially vertical flange 26, this flange being provided, preferably near its upper end, with a threaded opening 27 adapted to engage the threads of an adjusting or tightening screw 28 which is mounted in an opening 29 in the vertical inner wall 12 of the stationary member 6. The base 24 of the bracket 22 is further provided with an elongated slot 30 through which a shouldered screw 31 passes, this screw being firmly mounted in a threaded opening 32 in the base flange 13 of the member 6. A washer 33 is inserted between the head of the screw 31 and the base 24. It will be understood that the shoulder of the screw will be so selected with relation to the thickness of the bracket 22 and washer 33 as to provide an easy but accurate sliding fit for this bracket on the flange 13. The brackets 22 are relatively short in length and as many of these brackets are used as may be required to secure the necessary holding power. One of these brackets 22 is shown in a detached perspective view, Fig. 5.

Mounted on the flange 11 in the preferred form of my invention is a cover or semi-trough shaped bar 34. This cover-bar is formed with a groove 35 adapted to frictionally engage the flange 11. The upper surface of this cover-bar is formed with an arcuate surface 36 which terminates in the edge 37. This edge 37 is at a higher elevation than the balance of the bar when assembled as shown in Fig. 1, from which view it is evident that the cover-bar drains into the trough 9 at the lowermost point of the trough. This cover-bar 34 is clearly shown in the detached fragmentary perspective view, Fig. 6.

It will be evident from an inspection of Figures 3, 4, 5 and 6 that the elements used in this improved mounting are admirably adapted for production by the extrusion process. It will be understood that the brackets 22 illustrated in Figure 5 are readily cut from extruded bars. It will also be evident that the amount of machine work which must be performed on these bars is very small,

thus reducing fabrication costs to a minimum. It will also be apparent that the outer clamping member 15 has no openings, recesses or depressions in its face and is therefore easy to keep clean or polished.

The method of assembling and erecting this improved mounting is as follows:

The supporting member 6 is preferably prepared in the shop before shipment by cutting to suitable length and by drilling the necessary drain holes 10 and fastening holes 7, and by drilling a series of holes 29 in the vertical rear wall 12 of the stationary member 6 and drilling and tapping the holes 32 in the flange 13. The brackets 22 are then attached to the stationary member 6 by means of the shoulder screws 31, and the screws 27 are engaged with flange 26. This assembly, consisting of stationary member 6 with brackets 22 is then preferably shipped to the place of erection as an assembled unit. The outer clamping member 15 and the cover-bar 34 are likewise shipped to the place of erection.

In erection, the stationary member 6 is secured to the building frame in the desired location. The brackets 22 are then released by a rotation of the screws 27 in the proper direction until the sliding brackets occupy the position shown in Figure 7, access to the screws 27 being obtained through the opening 5 between the rear wall 12 of the stationary frame 6 and the display board 4, provided for this purpose. The screws 27 are provided with a hexagonal or other suitable head adapted to be rotated from above in case of the construction of Figures 1, 2 and 7, while flat-head screws 28^a may be provided for the flat display window construction illustrated in Figure 8. The glass 1 is then put in place, being supported on a plurality of wood blocks or other desirable supports which are not shown in the drawings as they are a common expedient well known to those skilled in this art. The outer clamping member 15 is then set in position as shown in the broken lines in Figure 7. The screws 27 are then rotated in the proper direction to draw the sliding bracket 22 inwardly until the outer clamping member 15 contacts the glass 1 sufficiently tightly. The cover-bar 34 is then sprung or forced in place on the flange 11 to complete the mounting.

In the event that a removal or renewal of the glass becomes necessary, the cover-bar 34 is removed and the tightening screws 28 are released until the outer clamping bar 15 can be lifted out, whereupon the glass can be removed.

It will be evident that the tightening bracket 22 is capable of slidable movement independently of the outer clamping member and it will be particularly clear that the bracket 22 can be moved to a position permitting the outer clamping member to be removed without necessarily moving this mem-

ber away from the glass. This has the evident advantage that any one or all of the brackets may be moved to the released position without distorting the outer clamping member or causing any undue strain either in the glass or clamping member.

Referring now to the form of my invention illustrated in Figures 11 to 13 inclusive, which likewise shows an application of this device to a store front construction, it will be apparent that the inner clamping member 6 and the cover-bar 34 are identical with these members described above. The outer clamping member 15' and the sliding brackets 22' differ slightly in this construction from the corresponding parts above described.

The outer clamping member 15' is formed with a lip 16' adapted to contact the glass 1 with a lower edge 17' adapted to contact the flange 13 of the stationary member 6. The intermediate portion 18' of this outer clamping member has a slightly different contour than that shown for the member 18. However, this forms no part of my invention and only indicates that various contours may be used with this type of mounting. Attached to this intermediate portion of the clamping member is a reversed lip 19' which is connected to the intermediate portion by a short vertical web 20'. The drain recesses 21' are provided in the lower edge 17' of this clamping member 15'. This outer clamping member is similarly formed by extruding, as will be understood.

35 Mounted for sliding movement on the horizontal flange 13 of the stationary member is a bracket 22'. This bracket is formed at the left or outer end with a reversed lip 23', adapted to engage the reversed lip 19' on the member 15', this lip 23' being connected to the base portion 24' of the bracket 22' by a vertical section 25'. The inner or rear end of this bracket is formed with a vertical flange 26', threaded opening 27' adapted to engage the threads of an adjusting or tightening screw 28' and the base 24' is provided with an elongated slot 30' in the same manner and for the same purpose as in bracket 22. It will be understood that these brackets 22' are preferably formed by cutting from a long bar of extruded metal and that as many of these brackets will be used as are necessary. One of these brackets 22' is clearly shown in perspective in Figure 12.

55 The method of erection of the members shown in Figures 11 to 13 inclusive is identically the same as that used for the structure shown in Figures 1 to 10 inclusive. Fig. 13 shows the sliding bracket in its released position and the outer clamping member in broken lines to show the ease with which this member may be put in place or removed.

It will be evident that the interlocking engagement of the reversed lips 23' and 19' forms an arcuate surface of contact as shown

in Figure 11, while the corresponding contact in the structure shown in Figure 1 is of a wedge nature and it should be pointed out that these types of contacting surfaces can be used interchangeably. The essential difference between the invention illustrated in Figures 1 to 10 inclusive and Figures 11 to 13 inclusive is that the resilience at the outer end of this mounting is provided in the vertical web member 20 in the first case and in the vertical arm 25' in the second case.

Figure 14 shows the invention of Figures 11 to 13 applied to a door frame 38, the only difference in the structure being such as may be made to satisfy the artistic ideas of the designer, the construction, operation and functions of the different members being substantially identical in both applications, no drain trough, however, being required for the application to the door, and an ogee wall 12^a being substituted for the vertical wall 12. Outwardly extending flanges 39 are also formed on the stationary member 6^a so as to provide suitable means for supporting this member on the door frame 38.

Figure 15 is a modified form of the device illustrated in Figures 1 to 10 inclusive and is shown principally to show that the contour of the outer clamping member 15^a may be varied to a remarkable degree with my invention, and that web 20^a supporting the reversed lip 19' is not limited to a vertical position.

In the mounting of glass windows, it is essential that the clamping means be resilient or yielding so as to eliminate unequal strains in the glass or local stresses on the glass which might cause fracture of the glass either in erection or in service due to the additional strains caused by the elements. In order to eliminate such excessive strains I provide the sliding brackets 22 with a relatively long flange 26 which is composed of resilient material and is so proportioned that the flange will yield or spring before excessive stresses can be transmitted to the edge of the glass by the screw 28 or by other agencies during service. In the form of device illustrated in Figures 11 to 14 inclusive, additional resilience is provided in the sliding bracket 22' by the substantially vertical arm 25'. In the form of device illustrated in Figures 1 to 10 inclusive and Figure 15, additional resilience is provided by the relatively thin depending web 20. The thickness of this continuous web 20 is so selected that it will be substantially equal in resilience to the series of arms 25' on the brackets 22' of the form shown in Figures 11 to 14 inclusive, as will be understood. It will thus be apparent that I have provided resilient elements associated with this improved tightening device which will eliminate danger of fracture of the glass not only in erection but in service.

In connection with the tightening and re-

leasing of the sliding bracket 22, it should be noted that the registry of the screw 27 in the opening 28 and the engagement of the slot 25 with the shoulder screw 26 provides 5 means for guiding the sliding bracket in a direction at right angles with the plane of the glass.

It should also be noted that the screw 27 is exerting its force in a direction parallel to 10 the resistance of the outer clamping member in all forms of this invention shown, and in the form illustrated in Figures 11 to 13 the screw exerts its force not only parallel to, but in line with the point of application of 15 the resistance of the clamping member to the sliding bracket. This arrangement insures a minimum of frictional resistance in the tightening device, causing the force of the screw to be directly transmitted to the clamping member and thus rendering the device 20 very sensitive to the touch whereby excessively tight clamping is avoided.

It will be understood that the size of plate 25 glass cannot be furnished to exact dimensions and that certain tolerance must be allowed. In order to accommodate oversize panes of glass, I have so arranged the parts of this mounting to clear a possible extension of the glass beyond expected limits. It will be clear 30 from the drawings that the tightening screws are of such length that they will not intersect the plane of the glass. Likewise the two ends of the sliding bracket are so located and their movement so limited that the vertical 35 projections at the ends of the sliding bracket do not intersect the plane of the glass in any position, and that the glass may extend substantially to the top of the base of the sliding bracket.

40 It will also be noted that the drawing force of the tightening bracket is applied to the outer clamping member at a point between its upper edge which contacts the glass and its lower edge which contacts the flange of the 45 stationary member, and in this manner the stress will be automatically distributed between the two contacting lines and will insure a water-tight joint at both places.

It will also be evident that the shape of 50 the reversed lip on the sliding bracket and the co-operating reversed lip on the outer clamping member will cause the outer clamping member to move toward the flange 13 of the stationary member 6 while the clamping 55 member is drawn toward the glass. In the forms illustrated in Figures 1 to 10 inclusive, these two co-operating surfaces very definitely are wedge surfaces. In the form illustrated in Figures 11 to 14 inclusive, the reversed 60 lip on the sliding bracket is in the form of a bead while this reversed lip on the outer clamping member presents an arcuate surface to the bead, these elements performing substantially the same service as the wedge 65 surfaces but to a somewhat less extent. This

tendency to draw the clamping member toward the flange 13 is especially advantageous for those cases where the reversed lip on the outer clamping member does not line up accurately with the recess formed under the reversed lip of the sliding bracket for any reason. In that case the wedge surfaces will cause the two members to register. 70

It is evident that the sliding brackets 22 and 22' may be located in any position along 75 the supporting member 6. It is often impossible to select a regular spacing for these brackets. For instance, it is usually desirable to locate a bracket close to the end of the outer clamping member in order that this 80 member may be accurately held at the joint which this clamping member makes with the adjacent clamping member. My invention lends itself readily to this variation in spacing as there is nothing on the outer clamping 85 member which must, in any way, register with these sliding brackets at any one spacing, in other words, the outer clamping member without alteration, properly co-operates with the tightening devices regardless of the 90 position of these devices on the stationary member. This results in considerable economy of fabrication as it is not necessary to space the brackets accurately, and because 95 no fabrication for connection process need be done on the outer clamping member. It should also be noted that those parts of the sliding brackets with which the outer clamping member must engage are in full view of the erector when he puts this member in place. 100 This is a decided advantage especially in erection, as compared with other mountings with which I am familiar as there are no threaded holes which must register with certain openings to permit the insertion of screws and there are no extensions or projections which 105 must be threaded under the glass to make engagement with certain elements which can not be seen by the erector.

The cover-bar 34 serves a dual purpose. First it provides an enlarged draining capacity without unduly enlarging the stationary member. This excess draining capacity is of considerable importance when windows are washed and the drippings from 110 the wiper run down in streams. The second purpose of this trough, of course, is to cover and completely conceal the adjacent screws so that a uniform and neat surface may be presented to the eye of the observer. The 115 smooth surface formed by this combination trough, being free from obstructions, is easy to keep clean.

It will also be evident from an inspection of 120 Figures 7 and 13, that the outer clamping member in both forms of this invention is substantially supported at two points as soon as it is placed in position, first on its lower edge on the flange 13, and second at an intermediate point on the bracket 22 or 22'. This 125

is an advantage in erection because there will be no tilting or slipping of these outer members during the tightening operation as these members move inwardly in a straight horizontal motion in a stable position.

5. What I claim is:

1. In a mounting for a glass window, a stationary member, a clamping member adapted to hold the window in position and means engaging the clamping member for drawing the same toward said stationary member, said means being movably mounted on the stationary member and in its released position being adapted to disengage the clamping member.
10. In a mounting for a glass window, an inner clamping member, an outer clamping member, an adjusting means associated with the inner clamping member and adapted to be detachably interlocked with the outer clamping member, said outer clamping member being adapted to be detached from the said adjusting means while said adjusting means maintains its association with the inner clamping member.
15. In a mounting for a glass window, an inner clamping member, an outer clamping member formed with a reversed lip, an adjusting means attached to the inner clamping member and provided with a hook member adapted to engage said lip and to disengage said lip while maintaining its attachment to the inner clamping member.
20. In a glass mounting a sill, an inner frame mounted on said sill and comprising a lip for contacting the glass, a substantially vertical inner wall and a substantially horizontal base, an outer frame, tightening means adapted to draw the outer frame toward the glass and mounted on said base, said tightening means including a resilient element, and means mounted upon said vertical wall for operating said tightening means.
25. In a glass window mounting a sill, an inner frame mounted on said sill and comprising a lip for contacting the glass, a rear substantially vertical wall and a substantially horizontal base, an outer frame, tightening means adapted to draw the outer frame toward the glass and mounted on said base, said tightening means including a resilient member and a screw member, said screw member being mounted in said rear wall of the inner frame.
30. In a window mounting, a stationary glass supporting member, a movable glass clamping member, means engaging with said movable member and adapted to draw the said member toward the stationary member, said means being permanently fastened to but slidably mounted on the stationary member, and being disengaged from the movable member when said means is in the released position.
35. In a mounting for a glass window, an inner frame mounted on said sill and comprising a lip for contacting the glass, a rear substantially vertical wall and a substantially horizontal base, an outer frame, tightening means adapted to draw the outer frame toward the glass and mounted on said base, said tightening means including a resilient element, and means mounted upon said vertical wall for operating said tightening means.
40. In a glass mounting, a stationary supporting member having a substantially vertical portion and a base portion, a movable clamping member, a bracket slidably attached to the base portion of the stationary member, a screw member mounted in the vertical portion of said stationary member, said bracket being formed with a reversed lip at one end adapted for engagement with said clamping member, and formed with a threaded opening at the other end adapted for engagement with said screw member.
45. In a glass window mounting a sill, an inner frame mounted on said sill and comprising a lip for contacting the glass, a rear substantially vertical wall and a substantially horizontal base, an outer frame, tightening means adapted to draw the outer frame toward the glass and mounted on said base, said tightening means including a resilient member and a screw member, said screw member being mounted in said rear wall of the inner frame.
50. In a window mounting, a stationary glass supporting member, a movable glass clamping member, means engaging with said movable member and adapted to draw the said member toward the stationary member, said means being permanently fastened to but slidably mounted on the stationary member, and being disengaged from the movable member when said means is in the released position.
55. In a window mounting, a stationary glass supporting member, a movable glass clamping member, means engaging with said movable member and adapted to draw the said member toward the stationary member, said means being permanently fastened to but slidably mounted on the stationary member, and being disengaged from the movable member when said means is in the released position.
60. In a window mounting, a stationary glass supporting member, a movable glass clamping member, means engaging with said movable member and adapted to draw the said member toward the stationary member, said means being permanently fastened to but slidably mounted on the stationary member, and being disengaged from the movable member when said means is in the released position.
65. In a window mounting, a stationary glass supporting member, a movable glass clamping member, means engaging with said movable member and adapted to draw the said member toward the stationary member, said means being permanently fastened to but slidably mounted on the stationary member, and being disengaged from the movable member when said means is in the released position.

7. In a glass mounting, a stationary supporting member, a movable clamping member, a slideable bracket, a screw member mounted in said stationary member, said bracket being formed at one end with a hook member adapted for engagement with said clamping member and being formed at the other end with a flange having a resilient portion which is adapted for engagement with said screw member.

70. In an adjusting device in a glass mounting, a slideable bracket comprising a reversed lip at one end and a screw element at the other end, the reversed lip and the axis of said screw element being substantially at right angles with the plane of the glass.

75. A bracket for use in glass mountings having one end formed with a lip projecting in a direction substantially at right angles with the plane of the glass, and the other end provided with a screw element, said bracket including a resilient portion between said lip and said screw element.

80. A bracket for use in glass mountings having one end formed with a lip and the other end with a screw element, said bracket including a resilient portion between said lip and said screw element, said lip projecting in a direction substantially parallel with the axis of the screw.

85. In a glass mounting, a stationary supporting member having a substantially vertical portion and a base portion, a movable clamping member, a bracket slidably attached to the base portion of the stationary member, a screw member mounted in the vertical portion of said stationary member, said bracket being formed with a reversed lip at one end adapted for engagement with said clamping member, and formed with a threaded opening at the other end adapted for engagement with said screw member.

90. In a glass mounting, a stationary supporting member, a movable clamping member, an adjusting means adapted for bringing the clamping member from its assembling position into clamping position with the glass, said adjusting means and said clamping member being adapted to permit the movement of the adjusting means from its clamping position to the assembling position while said movable clamping member remains substantially in its clamping position.

95. In a glass mounting, a stationary supporting member comprising a substantially vertical wall and a screw member mounted in said vertical wall, a movable clamping member formed with a reversed lip pointing in a direction opposed to the clamping movement of the said movable member, and a slideable bracket adapted for engagement with said screw member and with said reverse lip.

100. In a display window mounting, an

inner glass frame, an outer glass frame, adjusting means for drawing the frames toward each other, a portion of said adjusting means projecting inwardly from said inner glass frame and a cover-bar overhanging said projecting portion of the adjusting means.

15. A stationary window frame element comprising a moisture collecting trough formed with a lip adapted to contact the glass and a flange defining the opposite edge of the trough, combined with a detachable cover-bar having sliding engagement with said flange.

16. In a window mounting, an inner frame, a display board spaced from said frame, a cover-bar adapted to detachably engage said frame and span the said space between the frame and the display board.

20 17. In a display window mounting, a display board, an inner glass frame spaced from said display board, an outer glass frame, adjusting means adapted to draw said frames together, said adjusting means projecting from the inner glass frame and a cover-bar mounted on said inner frame and contacting said display board and adapted to conceal said adjusting means.

18. In a window mounting, an inner frame formed with a moisture collecting trough, and provided with means for attaching an extension bar adapted to widen said trough.

19. In a window mounting, a frame member provided with drain holes for moisture and a trough member removably mounted on said frame member and adapted to carry moisture to said drain holes.

20. In a window frame, an inner glass supporting member, an outer glass clamping member, a tightening device associated with the inner supporting member and adapted to form a detachable interlock with the outer clamping member, said tightening device being adapted to move outwardly independently of said clamping member, whereby said interlock is detached.

21. In a window mounting, an inner supporting member, a tightening device, an outer clamping member provided with means for interlocking with the tightening device, said tightening device adapted to hold the outer clamping member downwardly in its tightened position and adapted to permit the removal of the outer clamping member in its released position.

22. In a glass mounting, a supporting member, a plurality of tightening devices associated with the supporting member, a clamping member provided with a reversed lip pointing in a direction substantially opposed to the clamping movement of the clamping member and extending for the full length thereof and adapted to detachably engage said tightening devices, said clamp-

ing member and lip being located entirely on one side of a plane of the glass.

23. In a window mounting, a supporting member provided with a flange substantially at right angles with the plane of the window, a tightening device mounted on said flange, a clamping member having one edge adapted to rest against the window and having its other edge adapted to rest against said flange and having an intermediate point adapted to be removably supported on said tightening device when said device is in its released position.

24. In an adjusting device for a glass mounting, a slidable bracket, one end of which is formed with a reversed lip and the other end of which is adapted to co-operate with a screw element, said bracket being provided with means for limiting its sliding motion.

25. A mounting for glass windows comprising, inner and outer clamping members, a movable tightening member for one of said clamping members, and means for permanently fastening the other clamping member, said tightening member releasing and moving away from the first-mentioned clamping member over a part of its path of movement.

26. A mounting for glass windows comprising, inner and outer clamping members, a reciprocable tightening member for one of said clamping members, and means for permanently fastening the other clamping member, said tightening member releasing and moving away from said first-mentioned clamping member during its movement in one direction.

27. A mounting for glass windows comprising, a stationary back molding, a front clamping molding, and a tightening member for said clamping molding movably mounted upon said stationary molding, said tightening member releasing and moving away from said clamping molding over a part of its path of movement.

28. A mounting for glass windows comprising, a stationary back molding, a front clamping molding, and a tightening member for said clamping molding reciprocably mounted upon said stationary molding, said tightening member releasing and moving away from said clamping molding during its movement in one direction.

29. A slidable bracket for use in glass mountings having one end formed with a re-entrant lip and the other end provided with a screw element, said bracket being formed with an elongated hole permitting slidable mounting and having a resilient portion between said lip and said screw element.

30. A store-front construction comprising inner and outer members, the outer member formed with a depending longitudinal integral rib, a draw-bar formed at its outer end with an upwardly-extending stop engag-

ing with said rib and at its inner end with a wall, said draw-bar also formed between its ends with a longitudinally-elongated slot, a headed rivet extending through said slot 5 and into engagement with the base of the inner member, whereby said draw-bar is slidably connected with the said inner member, and a screw extending through the inner member and through said wall of the draw-
10 bar.

31. In a mounting for a glass window, an inner stationary member, an outer clamping member, said outer clamping member being formed with an outer wall and with a depending flange spaced from said outer wall, and means mounted on said inner member 15 adapted to engage said flange and to draw said flange toward said inner member.

32. In a mounting for a glass window, a stationary member, a clamping member formed with an outer wall and with a flange depending between said outer wall and said stationary member, and means mounted on the stationary member engaging said flange 20 25 adapted to draw said clamping member toward said stationary member.

33. In a mounting for a glass window, a stationary member, a clamping member, said clamping member being formed with a depending flange, and means adapted to draw 30 35 said flange toward said stationary member, said means being vertically fixed with relation to said stationary member and adapted to prevent the upward movement of said flange.

Signed by me this 2nd day of November,
1928.

ALBERT H. MARTY.
